UNITED STATES PATENT OFFICE.

BENJAMIN M. GRIFFITH, OF PITTSBURGH, PENNSYLVANIA, ASSIGNOR TO PITTSBURGH LAMP, BRASS & GLASS COMPANY, OF PITTSBURGH, PENNSYLVANIA, A CORPORATION OF NEW JERSEY.

DESIGN FOR A TOY MAGAZINE-GUN.

56,063.

Specification for Design.

Patented Aug. 10, 1920.

Application filed April 2, 1919. Serial No. 287,081. Term of patent 3½ years.

To all whom it may concern:

Be it known that I, BENJAMIN M. GRIFFITH, a citizen of the United States, residing at Pittsburgh, in the county of Allegheny and State of Pennsylvania, have invented a new, original, and ornamental Design for a Toy Magazine-Gun, of which the following is a specification, reference being had to the accompanying drawing, forming part thereof.

Figure 1 is a side elevational view of a

toy magazine gun illustrating my new design; and

Fig. 2 is a front elevational view thereof.

I claim:

The ornamental design for a toy magazine gun, as shown.

BENJAMIN M. GRIFFITH.
